(57) **CLAIM**

The ornamental design for a box for toy packing, as shown and described.

DESCRIPTION

FIG. 1 is a perspective view of a box for toy packing showing my new design;

FIG. 2 is a front elevational view thereof;

FIG. 3 is a rear elevational view thereof;

FIG. 4 is a left side elevational view thereof, the right side being a mirror image of that shown;

FIG. 5 is a top plan view thereof;

FIG. 6 is a bottom plan view thereof; and,

FIG. 7 is a perspective view thereof, showing environmental use.

The broken lines showing are for illustrative purposes only and form no part of the claimed design.
